EXPANDING REAMER

Filed Jan. 18, 1928

Inventor.
Edward F. Raymond.

Attorney.

UNITED STATES PATENT OFFICE

EDWARD F. RAYMOND, OF LOS ANGELES, CALIFORNIA, ASSIGNOR TO JOHN GRANT,
OF LOS ANGELES, CALIFORNIA

EXPANDING REAMER

Application filed January 18, 1928. Serial No. 247,582.

This invention relates to improvements in expanding drilling tools, underreamers or expansive reamers, and particularly to improvements in that type of reamer using 5 swinging expanding cutters; the improvements being mainly in the direction of providing a reamer of that type in which the whole reamer structure is exceptionally strong and solid, particularly when expanded 10 and operating. The features of the invention, however, will be best understood from the following detailed description of a preferred and specific form of reamer in which the invention is at present embodied.

15 In considering the following detailed description it will, however, be understood that the details of design and arrangement, except as hereinafter expressly set out in the claims, are not necessary limitations upon the 20 invention. For instance, one of the features of the invention is in the provision of swinging cutter carriers—carriers which swing on pivots to expand and contract—which are so formed and inter-related that in their expanded 25 positions they bear against each other and give each other support. This feature, as will be readily recognized, may be applied to any type of expanding drilling tool, reamer or underreamer, and with any type of 30 cutters. For illustrative purposes I shall show and explain the invention as particularly applied to an expanding reamer using roller cutters. And it will be recognized that various other specific features hereinafter 35 described are not necessarily limitative of the invention expressed in the accompanying claims.

For the purpose of specific description of an illustrative and preferred form and adaptation 40 of the invention, I refer to the accompanying drawings, in which:

Fig. 1 is a vertical central section of an expanding reamer embodying my invention;

Fig. 2 is a cross-section on line 2—2 of Fig. 45 1 showing the parts expanded;

Fig. 3 is a similar section showing the parts contracted; and

Fig. 4 is a cross-section on line 4—4 of Fig. 1.

50 In the drawings a suitable body is shown

at 10, this body having an upper head 11 and a relatively reduced shank 12 below the upper head, and in the particular form here illustrated the shank 12 as well as head 11 is shown as being cylindric. At the upper end 55 of the head the usual screw-threaded pin 13 is provided for connection with a drill stem; and the lower end of shank 12 has a similar screw-threaded pin 14 to which the shank of a drilling bit, or a connecting sub, 15, may 60 be screw-threadedly attached. Throughout the body a central circulation passage 16 extends from end to end to feed circulating fluid to the circulating passage or passages 15^a of the drill bit below. And, in order to 65 keep the swinging cutter carriers free, side circulation passages 16^a may lead from the main passage 16 to deliver circulating fluid to the swinging carriers.

The number of swinging carriers depends 70 upon the number of cutters desired; in this particular instance I have chosen to illustrate three. Thus there are three cutter carriers 20 designed, in this particular instance, to each carry a roller cutter 21 mounted on a 75 vertical mandrel pin 22 in the cutter carrier. Each cutter carrier is recessed as illustrated at 23 to accommodate its roller cutter, and the mandrel pins are mounted at their upper and lower ends in bores 24 and 25 in the parts 80 of the carrier which are respectively above and below the recesses 23. These upper and lower parts of the cutter carrier, indicated by the numerals 26 and 27, may be termed upper and lower heads, which are interconnected by the carrier web 28 which extends vertically between the heads. The mandrel pins may be arranged to be inserted from below, the upper bore 24 extending only part 85 way upwardly through the upper head 26, but the bore 25 extending vertically clear through the lower head 27, and the mandrel pin being supported by a screw-threaded plug 29 as illustrated in Fig. 1.

Each cutter carrier has at its upper and lower ends two pivot pins 35 and 36, the two pins for each carrier being arranged on a common vertical axis in substantially the relationship to the cutter axis that is shown in Figs. 2 and 3. The upper pivot pins 35 are 95 100

journalled in bores 37 in the upper body head 10; while the lower pivot pins 36 are journalled in bores 38 in a lower bearing collar 39 which fits removably upon body shank 12. Bearing collar 39 is removable from the body shank by longitudinal movement but is rotatively fixed upon the shank in any suitable manner, as by a key or spline such as illustrated at 40 in Fig. 1. The sub or drill shank 15 holds bearing collar 39 up in place and holds the whole tool in assembly.

It is preferable to provide some spring means for urging the cutter carriers toward their expanded positions. Any suitable spring means may be utilized, but I have here preferred to show coiled torsion springs 45 fixed in the body at their upper ends at 46 in the upper ends of bores 37, and attached at their lower ends to spring heads 47, which heads have flat keys 48 adapted to enter slots 49 in the upper ends of pivot pins 35. These springs tend to urge the cutter carriers from the position of Fig. 3 to the position of Fig. 2.

The characteristic form of the cutter carriers is shown in Figs. 2 and 3 and will now be described. The exterior surface 50 of each cutter carrier may preferably be curved and concentric with the center of the tool when the carriers are expanded, as shown in Fig. 2. The cutter carrying end of each carrier has a curved cylindric surface 51 concentric with the axis of its pivot pins 35 and 36. The opposite or tail end—the end of the swinging cutter carrier on the opposite side of the swinging axis from the cutter carrying end—has a curved cylindric surface 52 of the same radius of curvature as surface 51 and so placed and arranged upon the carrier, that, in the expanded positions, a surface 52 at the end of one carrier bears against surface 51 at the adjacent cutter carrying end of the next carrier. It will be noted that, due to the described relationships of the swinging axes and surfaces 51 and 52, the engagement of a surface 52 with a surface 51 forms a stop to limit the outward swinging movement of the cutter carrying end of each carrier (swinging movement of each carrier in a left-handed direction about its own pivot). Also each cutter carrier has on its inner face, and near its cylindric face 52, a cylindric stop face 53 which, in expanded position, bears solidly against the body shank 12. On its inner face at its cutter carrying end each carrier has a cylindric face 54 which bears against body shank 12 when the cutters are contracted. The outer faces of the carriers are made up of the outer cylindric surfaces 50 hereinbefore referred to, and flat end surfaces 55 and 56, which flat surfaces, when the carriers are expanded, lie in pairs (55, 56) in common planes such as illustrated in Fig. 2, giving a sort of triangular cross-section to the composite body which is made up of the three cutter carriers when expanded.

The particular inter-engaging shapes of the cutter carriers may be confined to their two heads, or may extend along the whole lengths of the carriers. If they do so extend along the whole lengths of the carriers, it will be seen that, in the expanded operative position, an interlocking and inter-engaging aggregate of cutter carriers is provided in such a manner that the aggregate presents exteriorly only the vertical cylindric faces 50 and the plane faces 55 and 56, without any recesses or pockets except the recesses which are occupied by roller cutters 21. This gives a smooth exterior surface not liable to catch and hold mud or other foreign matter and one which is most easily rotated with the least drag. At the same time it will be noted that the inter-engaging faces of the several cutter carriers gives the carriers an exceptionally good support against the radial and circumferential thrusts to which the cutters and the carriers are subjected during active drilling. This support of the cutters against circumferential thrust and against torsions tending to swing them further outwardly, is provided not only by bearings against the body but also by bearings of the carrier ends against each other. It will be noted that, although the inter-engaging cylindric faces 51 and 52 support each carrier against circumferential thrust, they do not interfere at all with collapsing action of the cutters, due to the fact that they are concentric about the corresponding pivotal axes.

I claim:

1. In an expanding reamer or the like, a plurality of swinging cutter carriers mounted to swing on longitudinal axes which are spaced around a central axis of the body, each carrier having a cutter carrying end to one side of its swinging axis and having a tail end extending to the other side of its swinging axis, and each carrier having at its cutter-carrying end a surface engageable by the tail end of an adjacent carrier. 100
2. In an expanding reamer or the like, a plurality of swinging cutter carriers mounted to swing on longitudinal axes which are spaced around a central axis of the body, each carrier having a cutter carrying end to one side of its swinging axis and having a tail end extending to the other side of its swinging axis, and each carrier having at its cutter-carrying end a surface engageable by the tail end of an adjacent carrier, the inter-engaging surfaces of the head and tail ends of any two adjacent carriers being, when the cutter carrying ends are swung outwardly, substantially concentric about the swinging axis of the carrier whose cutter carrying end surface is being engaged. 115
3. In an expanding reamer or the like, a plurality of swinging cutter carriers mounted to swing on longitudinal axes which are spaced around a central axis of the body, 130

each carrier having a cutter carrying end to one side of its swinging axis and having a tail end extending to the other side of its swinging axis, and each carrier having at its cutter-carrying end a surface engageable by the tail end of an adjacent carrier, each carrier also having an inner surface engageable with the body when the cutter carrying ends of the carriers are swung outwardly.

10 4. In an expanding reamer or the like, a plurality of swinging cutter carriers mounted to swing on longitudinal axes which are spaced around a central axis of the body, each carrier having a cutter carrying end to one side of its swinging axis and having a tail end extending to the other side of its swinging axis, and each carrier having at its cutter-carrying end a surface engageable by the tail end of an adjacent carrier, the inter-engaging surfaces of the head and tail ends of any two adjacent carriers being, when the cutter carrying ends are swung outwardly, substantially concentric about the swinging axis of the carrier whose cutter carrying end surface is being engaged, each carrier also having an inner surface engageable with the body when the cutter carrying ends of the carriers are swung outwardly.

20 5. In an expanding reamer or the like, the combination of a body, a plurality of cutter carriers mounted to swing on longitudinal axes which are arranged about a central axis of the body, a cutter carried at one end of each carrier to one side of its swinging axis, and each carrier having a tail end projecting to the other side of its swinging axis, and the cutters being so formed that, when their cutter carrying ends are swung outwardly they engage the cutter carrying end of one with the tail end of another.

30 6. In an expanding reamer or the like, the combination of a body, a plurality of cutter carriers mounted to swing on longitudinal axes which are arranged about a central axis of the body, a cutter carried at one end of each carrier to one side of its swinging axis, and each carrier having a tail end projecting to the other side of its swinging axis, and the cutters being so formed that when their cutter carrying ends are swung outwardly they engage the cutter carrying end of one with the tail end of another, and each cutter carrier having an engagement surface which bears against the body when the cutter carrying ends of the carriers are swung outwardly.

40 7. In an expansive reamer or the like, the combination of a central body, swinging cutter carriers mounted on longitudinal axes spaced around the central axis of the body, the carriers each having cutter carrying ends to one side of their respective axes and having swinging tail ends to the other side of their said axes, and the several carriers interengaging when their cutter carrying ends

are swung outwardly to present an exterior aggregate surface unbroken by recesses.

In witness that I claim the foregoing I have hereunto subscribed my name this 20th day of December, 1927.

EDWARD F. RAYMOND.
